Primary Examiner — Dana L Meyrow

(74) Attorney, Agent, or Firm — Karen E. Klumas

(57) **CLAIM**

The ornamental design for a bottle, as shown and described.

DESCRIPTION

FIG. 1 is a perspective view from above and one side;

FIG. 2 is a front elevational view;

FIG. 3 is a rear elevational view;

FIG. 4 is a side elevational view;

FIG. 5 is an elevational view of the other side;

FIG. 6 is a top plan view; and,

FIG. 7 is an underneath plan view.

In FIG. 7, the dot-dot-dash broken line defines the bounds of the claimed design and forms no part thereof.

1 Claim, 5 Drawing Sheets
